PROCESS FOR PURIFYING OIL BY
DISTILLATIONCharles J. Egger and Robert H. Webster, Cleve-
land, Ohio, assignors to The Buckeye Labora-
tories Corporation, a corporation of Ohio

Application July 9, 1945, Serial No. 603,856

1-Claim. (Cl. 196—16)

1

Our invention relates in general to distillation and more particularly to apparatus and process for separating fluids of divergent boiling points. In recent years, there has been a rapid development of flash-distillation and allied processes for handling easily decomposable fluid in distillation and separation. Processes, and equipment for carrying out the processes, have been developed in recent years for such purposes as recovering of by-product organic compound; cleaning and recovery of used and contaminated oils such as lubricating and rolling oils; and the dehydrating and degasifying of fluids. Many of these processes and the equipment for the processes, have operated with only a part of the system employing the flash-distillation principle while others were directed almost in their entirety to the flash-distillation principle. Further, although at first analysis they may appear quite similar, two widely divergent principles are followed in operating various types of flash-distillation equipment. First of these, is the process which attempts to vaporize all but the extremely high boiling point constituents and solids. This process attempts to turn all of the fluids entering the still into gases for subsequent selective condensation. In this type of equipment and process, the gases leaving the still are generally strained through a scrubbing medium of loose materials in order to retain any entrained solid matter and unvaporized heavy liquid material. The second method, is to apply only enough heat to vaporize unwanted constituents and permit the remaining constituents to be removed from the still as a liquid.

It is the second mode of operation to which our invention relates. In the past, many attempts have been made to separate fluids of widely divergent boiling points by pumping them at a high pressure into a low pressure zone and atomizing the fluids in order that a maximum amount of surface area might be presented to the influence of the low pressure zone, and thereby throw the more volatile constituent into the gaseous phase and thus be removed from the higher boiling point constituents. However, it is always found that a considerable percentage of the material desired to be separated out was always found in the finished product when using the standard equipment for this process.

After considerable study and development, we have discovered that the weakness of the present known methods has been the failure to recognize the need for supplying the extremely large amount of sensible heat absorbed by liquid ma-

terials when volatilized and expanded. The heat absorbed by the volatilization is known technically as the heat of vaporization. We have found, that the amount of heat absorbed by the constituents being volatilized is so great that the temperature within the still was oftentimes reduced to a temperature insufficient to cause volatilization of the incoming impurities. Therefor, these impurities remain with the treated materials leaving the still. Further, it has been found that after atomizing the contaminated or mixed material, a complete separation has not been accomplished by the time the spray is recollected, and therefore requires a longer exposure to the reduced pressure of the still. However, while being further exposed to the reduced pressure area, the fluids must be maintained at a high temperature lever in order to continue to supply the latent heat of vaporization required for the remaining volatile constituents. That is, if the atomized fluids are allowed to contact a cold surface, or return over cold surfaces to a sump for collection, the volatile constituents have no chance to volatilize and therefor remain with the treated materials. We have found that in order to effect a complete and satisfactory separation of these volatile materials from the less volatile materials, the distillation zone into which the materials are atomized, must be maintained at substantially the same temperature level at all times, and the walls of the chamber, and other surfaces which the fluids might strike or touch, must also be maintained at substantially the same constant temperature.

Also, we have discovered that in separating volatile constituents, a type of apparatus is required that will permit the vaporized portion to be carried away, and not accumulate in dead pockets within the still. That is, if a dead pocket of the volatilized portion were to collect, and the atomized spray of incoming materials passed therethrough, the atmosphere surrounding the spray would be saturated, and the volatile constituents would remain as liquid to carry off with the liquid portion. This action is akin to human perspiration on rainy days as compared to dry days. Our improved apparatus affords complete and quick removal of volatilized materials.

Therefor, an object of our invention is to provide a process for the substantially complete separation of fluids of divergent boiling points for the removal of contaminants from oil.

Another object of our invention is to supply additional heat to a previously heated con-

glomeration of fluids of divergent boiling points while being distilled at sub-atmospheric pressures and while in the finely dispersed state to obtain complete vaporization of all the volatile components of the conglomeration desired to be removed, and to prevent condensation of the vaporized volatile components within the distillation chamber.

Another object of our invention is the provision of spray atomizing a conglomeration of fluids of divergent boiling points into a sub-atmospheric pressure chamber and thereafter interrupting the spray by means of a fluid film exposing device capable of collecting the atomized spray and dispersing same over a multitude of tortuous path surfaces to increase the length of time which the conglomeration of materials is exposed to the action of the sub-atmospheric pressure.

Another object of our invention is the provision of supplying heat of vaporization and thermal energy of expansion by direct heat to the vaporization area in which the expansion is carried out.

Another object of our invention is to provide a process and apparatus for isothermal flash-distillation to separate a conglomeration of materials of divergent boiling points.

Other objects and a fuller understanding of our invention may be had by referring to the following description and claim taken in conjunction with the accompanying drawings, in which:

Figure 1 is a cross-sectional view taken along the line 1—1 of Figure 2;

Figure 2 is a longitudinal cross-sectional view taken along the line 2—2 of Figure 1;

Figure 3 is a cross-sectional view taken along the line 3—3 of Figure 4; and

Figure 4 is a longitudinal cross-sectional view taken along the line 4—4 of Figure 3.

To achieve a separation of fluids of divergent boiling points mixed together in a conglomeration, such for example, as fluid dissolved in fluid, gases dissolved in fluid, and mixtures of fluid, or any combination or combinations of the aforesaid types, it is necessary to use some convenient form of distillation, and all known methods of commercial treatment contemplate the use of this type of physical action. Many means have been devised to accomplish this separation rapidly, completely, and effectively, but all have comprehended the separation being done by distillation of considerable quantities of the conglomeration. Consequently, an appreciable time interval elapses between the introduction of heat and pressure change, and the completion of the removal of the volatile portion. Also, to accomplish final removal of the last traces of the volatile portion from a quantity of the original conglomeration, thermal energy is applied at an increasing rate. While this is being done, conditions exist in the conglomeration frequently favorable to breaking down some of the desirable constituents, with formation of additional undesirable constituents and products of lower molecular weights. These break-down products are of lower boiling points, usually sufficient in degree and amount to cause them also to be classified as volatile constituents, and therefor should also be removed. Before a completely desirable result is achieved, it is frequently found that the final yield and separation of the volatile constituents from the less volatile constituents has been unsatisfactory from an economical standpoint. If the distillation be not carried on with this degree of thoroughness, the presence of constant boiling mixtures will frequently cause the final prod-

uct to be considered not totally satisfactory in regard to desirable physical characteristics.

If, however, a comparatively small amount of the conglomeration be subjected to a distillation process at sub-atmospheric pressure, and if this quantity be extended to present the greatest possible surface to this sub-atmospheric action, it is found that the separation is achieved with a degree of completeness not previously possible, and in a period of time which does not permit any observable degradation of the desirable constituent of the conglomeration. In order to present maximum surface, it is necessary either to present a continuous film of negligible thickness, or to disperse the conglomeration in exceedingly fine globules. The existence of either of these forms must exist for a period of time sufficient to assure the separation of the lower boiling point constituents from the higher boiling point constituents of the conglomeration. From the standpoint of control of operating conditions, it has been found to be more satisfactory to present discreet globular particles to the combined action of heat and reduced pressure, than to extend a continuous film, only one surface of which can be presented to the sub-atmospheric pressures and spaces.

One of the features of our invention is the provision of heat for the walls of the chamber independently of the heating of the conglomeration to be treated. For example, we have found that if the conglomeration is first raised to a temperature sufficiently high to assure enough heat energy for the heat of vaporization for the volatile portion, it is entirely possible that the volatilization of the more volatile constituents by distillation will be practically complete even though the vaporization is carried out in a chamber that is not supplied with our improved heated wall condition. If however, the vaporized portions have occasion to come in contact with the walls of the chamber which are at a much lower temperature, condensation occurs on the walls and an appreciable amount of the volatile constituents will flow down the sides of the chamber and combine with the less volatile constituents which have been freed from the more volatile constituents by the fractional distillation which has already occurred. The final result is therefore that the volatile portions are removed from the conglomeration being treated, and subsequently reincorporated to some degree.

We have found that by maintaining the walls of the chamber in the area of the spray and evaporation, and preferably by maintaining all of the walls of the chamber at an elevated temperature, we have contributed substantially to the efficiency of the process. We have found that the walls of the chamber should be maintained substantially equal to, or slightly above, the temperature of the conglomeration of fluids at the point of introduction into the chamber. By maintaining the walls at a temperature as thus described, we have fulfilled two conditions necessary for successful operation. In the first place, for successful operation, there must be no flow of heat from the conglomeration, or from the vaporized volatile portion, to the wall. To allow such flow of heat would result in condensation of the volatilized portion with the result that the vaporized portion would be returned to the treated material. Secondly, because a large amount of heat is required to supply energy for expansion of the conglomeration within the chamber and to supply the latent heat of vaporization for the removal of the volatile portion,

supplying additional heat through the walls of the chamber to the conglomeration at the point of the spraying and the volatilization reduces the need for heating the original conglomeration to an unduly high temperature in an effort to supply the heat directly to the conglomeration before entering into the chamber. That is, the original conglomeration may be heated to a safe temperature limit before being spray atomized into the chamber, and the additional heat required for the expansion and vaporization is readily supplied through the walls of the chamber as it is required.

Our invention comprehends the application of the principles explained in a manner which is efficient and economical. The preferred apparatus employed is shown in the drawings and the process will be understood when reference is made to them while the operation is explained.

As will be seen, the requisites for carrying out our process employ a means of supplying the conglomeration through a supply line 14. The conglomeration is pre-heated by passing through a heat exchanger 15 and is placed under a relatively high pressure by a pump 16. The conglomeration then progresses to a heater 17 which may be conveniently heated by electrical heating elements of any suitable design, or by steam or other suitable devices if desired. The conglomeration is then introduced into an evacuated expansion chamber 11 by spray atomizing the same through a spray nozzle 18 whereby it is dispersed into exceedingly fine globular particles projected into the space enclosed by the chamber 11. The chamber 11 is maintained at sub-atmospheric pressure by means of a vacuum pump 19. It is desirable in many applications to use a condenser 20 as illustrated connected between the chamber 11 and the vacuum pump 19 in order to condense the volatilized portions of the conglomeration which are carried off by the action of the vacuum pump 19.

The chamber 11 is surrounded by an insulated housing 10 to provide an air space 12 which may be heated to any suitable desirable temperature by heater means, such as heater rods 13. The heater rods 13 may be connected to any suitable electrical outlet and they warm the air in the space 12 and thus maintain the walls of the chamber 11 at a temperature at least as high as the temperature of the conglomeration which is introduced into the chamber 11 in order to prevent condensation of the vaporized volatile components within the chamber 11. The atomized material is indicated by the reference character 29 and is so directed by the spray nozzle 18 that it impinges against a fluid surface exposing device 22 where the atomized material is collected as a thin film and is outwardly dispersed to collect in a collecting gutter 25. The collecting gutter 25 is perforated at its lower edge as illustrated by the reference character 26 in the Figure 1. The fluid material thus collected in the gutter 25 may drip freely through the openings 26 and drip downwardly in a direction countercurrent to the direction of the spray 29 and is intercepted in the lower portion of the chamber 11 by a baffle arrangement 28. The baffle arrangement 28 permits the returning components to flow in a thin film surface for an extended period of time as it progresses to the lower level of expansion chamber 11 which will serve as a fluid sump. The treated components are removed from the chamber 11 through a conduit 33 and passed through a heat exchanger 15

where the sensible heat contained therein is transferred to a certain extent to the incoming conglomeration as previously described. The treated materials may be maintained at a constant level in the sump portion of the chamber 11 by means of a constant level cap 32 positioned at the intake end of the conduit 33. The cap 32 thus maintains a constant level in the sump portion of the chamber 11 to seal the conduit 33 from the action of a vacuum within the chamber 11, but affords immediate removal of the excess material from the chamber 11. Thus, no accumulation is present beyond the desired sealing level at any time in the chamber 11 to decrease its defective space or capacity. The process may be carried out continuously without interruption, and tests show that the process and equipment afford substantially a complete separation as desired.

It is of course understood, that the greatest amount of surface may be obtained in a fluid material by spray atomizing the material rather than providing a thin film surface. However, a chamber suitable for spray atomizing a liquid from a relatively high pressure into the chamber held at a relatively low sub-atmospheric pressure, and which would be large enough to permit the spray to ascend as far as possible without striking any surface, would be unduly large and impractical. Therefor, the fluid surface exposing device 22 is employed, against which the spray 29 may impinge and be interrupted in its upward direction. In our apparatus, this device 22, we have found, produces the greatest amount of surface area for fluid deposited upon a surface. The device 22 comprises two screen holders 24 positioned one above the other and containing a multitude of small particles such as raschig rings, beryl saddles, glass beads, or other loose materials including glass wool, mineral wool and steel wool. The device 22 is substantially cone shaped with its apex extending upwardly in the center and the side descending therefrom towards the gutter 25. Thus, the spray 29 impinges against the device 22 and is there interrupted in its upward path of travel by the multitude of small particles 23. The fluid portion of the conglomeration is thus collected upon the surface of the particles 23 and is continuously moved from one particle to the other outwardly and downwardly by the force of the oncoming spray 29. During the time when the fluid portion of the conglomeration is thus deposited upon the surface of the particles 23, it is in a very thin film stage and is continuously exposed to the action of the vacuum within the chamber 11. Thus, any small amount of material to be volatilized which has not already been removed during the atomized state between the nozzle 18 and the fluid surface exposing device 22, will be given an opportunity to volatilize and escape. Also, the small particles 23 provide a ready path for the volatilized constituents to pass therethrough and be exhausted through the condenser 20 and vacuum pump 19. Further, the remaining fluid portion which is collected in the trough 25 and allowed to drip countercurrently to the spray 29 as described, is further exposed for a period of time to the action of the vacuum within the chamber 11 while running over the baffle device 28 to the fluid pump portion of the chamber 11.

Another suitable apparatus to carry out the process is illustrated in the Figures 3 and 4 of the drawing, and comprises a vacuum chamber 75 35 of substantially cone shaped cross-section,

Thus, the remaining liquid components of the original contaminated material are returned to the sump portion of the chamber 35 by running in a thin surface area from the openings 26 of the trough 25 along the tapering heated surfaces of the cone shaped chamber 35. Thus, it will be seen, that the cone shaped chamber 35 replaces and eliminates the need for the baffle means 28. In fact, the cone shaped chamber 35 provides a warm surface upon which the returning fluid may flow in order to assure a supply of sensible heat to cause complete volatilization of the volatile impurities.

In both the straight and the cone shaped devices, we usually provide at least one vision port 31 in order that the operator may visually inspect the condition existing within the chamber.

The process and apparatus described herein has not been limited to any specific fluid or conglomeration of fluids, because we have found that the device and process is equally successful with a large number of various fluids. For example, this process and equipment has been used successfully for restoring various contaminated oils such as heat transfer oil used for quenching purposes in hardening of steel, electrical insulating oil, engine oil, lubricating oil for vacuum pumps and the like, refrigerator lubricating oils, for degasifying beverage waters, and for degasifying and dehydrating various fluids. That is, the process and equipment is equally successful for removing undesirable constituents, for dehydrating, and for degasifying. Also, it has been found that each fluid treated requires a different temperature, pressure, and vacuum. Thus, whereas one fluid may require a relatively high preheat temperature, another fluid may actually require refrigeration before being atomized within the expansion chamber. In all cases, however, the walls of the expansion chambers are easily adjusted in temperature to maintain them at exactly the proper temperature to conduct sensible heat therethrough to maintain the interior of the chamber at exactly the desirable degree of temperature while in operation.

Although we have described our invention with a certain degree of particularity in its preferred form, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

Process for fractionally separating contaminating materials of unlike boiling points in oils, comprising the steps of preheating a conglomeration of oil having said materials to an elevated

temperature, providing a chamber having side walls and top and bottom end walls sealed vacuum tight, and having a fluid surface exposing means near the top end wall of the chamber, evacuating said chamber to a sub-atmospheric pressure by withdrawing vapors from the area of the chamber between the said fluid surface exposing means and the top end wall, said elevated preheat temperature being sufficiently high to vaporize at said sub-atmospheric pressure the highest boiling point material to be removed, but said temperature being below the vaporization and decomposition temperature at said sub-atmospheric pressure of the oil to be retained as a liquid, spray atomizing said preheated conglomeration in said chamber from a position near the bottom end of the chamber in an upward direction toward said fluid surface exposing means and simultaneously supplying sensible heat through said side wall of said chamber, said sensible heat being sufficient in value to maintain the side wall of said chamber at a temperature at least as high as the boiling point within the chamber of the highest boiling point constituent to be removed to prevent condensation thereof, and being sufficient in value to supply the heat of vaporization absorbed by volatilization of the constituents to be removed, which sensible heat value together with the heat units in the heated oil itself provide full separation of the contaminants from the oil without overheating and destroying the oil, intercepting the remaining liquid oil portion of said conglomeration on said fluid surface exposing means, said intercepted liquid oil portion thereby being exposed to the action of said sub-atmospheric pressure and to said sensible heat for a period of time as a thin film upon the fluid surface exposing means, returning the intercepted liquid oil by gravity in a countercurrent direction to the original spray direction to the bottom end of the chamber, and withdrawing from the chamber the collected liquid oil in the bottom of the chamber.
